UNITED STATES PATENT OFFICE

JOHN CONRAD STRICKLER, OF SAN FRANCISCO, CALIFORNIA, ASSIGNOR TO AMERICAN CAN COMPANY, OF NEW YORK, N. Y., A CORPORATION OF NEW JERSEY

SUCTION CUP

Application filed September 17, 1931. Serial No. 563,818.

The present invention relates to a suction cup for use in connection with the separation or feeding of flat articles such as sheets or strips and an object of the invention is to provide a suction cup which raises and separates a sheet from a stack of sheets while rapidly vibrating so as to shake off any other sheet or sheets which cling to the engaged sheet during this separation, thus insuring lifting of only a single sheet at a time.

Suction cups are used for numerous feeding operations for sheets, strips and other flat-sided articles, one particular use of a suction cup being found in the metal forming art for the automatic feeding and separation of sheets or strips in automatic die presses and it is for such a use that the vibrating cup, herein illustrated and described, has been selected as a preferred embodiment of the present invention.

The principal object of the present invention is the provision of a suction cup formed with at least two elements so that relative vibrating movement may be had between a relatively rigid part and a movable article engaging part.

An important object of the invention is the provision of a suction cup of the character described wherein the suction used for lifting and holding a separated sheet or article is also utilized for vibrating the cup during such separation.

A further important object of the invention is the provision of a suction cup of the character described which is compact and self-contained and which automatically opens and closes vacuum and atmospheric valve ports so that a vibrating movement is given to the sheet engaging part of the cup during separation of it from a stack.

Numerous other objects of the invention will be apparent as it is better understood from the following description, which, taken in connection with the accompanying drawing, discloses a preferred embodiment thereof.

Referring to the drawing:

Figures 1, 2 and 3 are transverse sectional views taken through a vibrating suction cup employing the present invention, the various

views illustrating different positions of the cup from the time of first engagement with a stack of sheets as in Fig. 1, through the two extreme vibrating strokes of the cup illustrated in Figs. 2 and 3.

While suction cups for lifting a single article or sheet directly engages only a single sheet, it frequently happens that a second or third sheet adheres to the sheet engaged and accordingly two or more sheets are lifted when only a single sheet is desired. The present invention is particularly concerned with shaking loose any adhering sheets which may be incorrectly lifted at such a time and this is accomplished by a vibration of a part of the cup which is the result of relative movement between a movable and a rigid part. Two parts of the cup are preferably formed as elements of an air cylinder and piston device which connects with the source of vacuum used in the suction cup, the position of the piston relative to the cylinder automatically closing or opening the necessary ports to vacuum and atmosphere to effect a rapid vibrating movement.

Such a suction cup may be suitably mounted on a conduit pipe 21 which is raised and lowered in proper time with the working parts of the machine with which the cup is associated. A cup frame 22 is clamped by means of a bolt 23 to the pipe 21 and is formed with a cylindrical hollow section 24 enclosing a chamber 25. The vibrating or movable part of the cup is mounted in part within the chamber 25, this member comprising a piston head 26 located within the cylinder 24 and a stem 27 projecting downwardly from the piston head and having sliding movement in an opening 28 formed in the bottom of the cylinder.

The stem 27 is formed with a conical bottom 31 against which an article engaging suction cup rubber 32 is clamped by a screw 33 threadedly engaged within the lower end of the stem and having a head 34 engaging the underside of the suction rubber and squeezing the engaged portion against the wall 31.

A stack of articles, such as sheets 41, represent the work designed to be separated by the suction cup, this stack being suitably sup-

ported on a base 42 which may be any suitable part of a magazine or other part of the associated machine. The upper end of the cylinder 24 is closed by a cap 43 secured in position by bolts 44. The piston head 26 and its stem 27 is preferably cored out or made hollow to provide a lighter, more movable element. Its hollow interior is only dead air space, the upper wall of the head being formed by a plate 45 swedged or otherwise held in sealed position.

The interior of the pipe 21 is in communication with a source of vacuum and a port 47 formed in the pipe communicates with a similar port 48 formed in the rigid cup body 22 adjacent and these ports communicate with a vertical air passage 49 formed in the side wall of the cylinder 24. A lateral port 51 communicates with the lower end of the passage 49 and connects the lower part of the chamber 25 with the source of vacuum, this connection being made below the piston head 26.

Lateral ports 55, 56 and 57 are formed in the cap 43, to provide the desired connection between the upper part of the chamber 25 and the source of vacuum, this connection being above the piston. A central air passage 61 is formed in the vibrating member 30 and a continuing and similar air passage 62 is formed in alignment in the clamping screw 33.

Prior to the suction cup engaging a sheet 41, air is drawn through the passageways 62, 61, 57, 56, 55, 51, 49, 48, 47 and through the conduit pipe 21 but no work is accomplished. The vibrating member at such time is in a lowered position relative to the body 22, its piston head 26 resting against the bottom of the cylinder 24. As soon as the rubber 32 engages the upper sheet 41, this being brought about by lowering of the suction cup for a separating operation, a chamber 63 is formed below and inside of the rubber 32, the lower end of this chamber being closed by the engaged sheet 41. Fig. 1 shows this position of the cup.

Air is immediately withdrawn from the chamber 63 and at the same time the suction cup is raised lifting the engaged sheet 41, which adheres to the cup, from the stack. Simultaneously with this action air is also withdrawn from the chamber 25 and the atmospheric pressure against the undersurface of the sheet by reason of the rarefied atmosphere within the cylinder causes the vibrating member to move up into its uppermost position (Fig. 2).

In this position a valve rubber 65 embedded in the plate 45 of the vibrating member engages the undersurface of the cap 43 and closes the port 57 cutting off further vacuumization of the chamber 25 above the cylinder head. At the same time a vertically

raised through an opening 67 formed in the cap 43 and a slot or flattened side 68 cut in the pin comes into position adjacent the opening. This slot extends above the top of the cap 43 and forms an air passage connecting the chamber 25 with the outside atmosphere. Air immediately rushes into the upper end of the chamber and partially diminishes the vacuum therein. Thereupon the vibrating member and the sheet held thereon drops from the position illustrated in Fig. 2 into the position illustrated in Fig. 3, this latter position being the lower working position of the vibrating member within its rigid cylinder.

In this latter position the opening 67 is again closed by the unslotted part of the pin 66 and the port 57 is uncovered. The air within the chamber 25 is again removed through the conduit pipe 21 and the vibrating member is again lifted into its uppermost position. This shifting of the vibrating member from one position to another takes place very rapidly and imparts a vigorous shaking movement to the sheet so that in the event that other sheets adhere to the separated sheet these will be shaken loose. The action is so rapid and the degree of vacuum pull through the supply pipe 21 so relatively great compared with the small amount of air passing through the vent 67 that such a shaking action is not sufficient to disengage the sheet held directly by the suction rubber 32. It is sufficient to insure the proper separation of a single sheet from the stack.

The sheet may be removed from the suction cup by any suitable mechanism, depending upon the kind of apparatus in which the suction cup is embodied. The chamber 63 thereupon being open to atmosphere the cup parts are restored to normal position ready for the succeeding sheet engagement.

It is thought that the invention and many of its attendant advantages will be understood from the foregoing description and it will be apparent that various changes may be made in the form, construction and arrangement of the parts, without departing from the spirit and scope of the invention, or sacrificing all of its material advantages, the form hereinbefore described being merely a preferred embodiment thereof.

I claim:

1. A vibrating suction cup for article separation, comprising a vibrating member carrying an article engaging element, means for applying a pulsating suction to said member and element to sustain the article and vibrate said member.

2. A vibrating suction cup for article separation, comprising a vibrating member carrying an article engaging element, means for applying suction to said element and said member, and means for periodically venting said member to vibrate said member.

3. A vibrating suction cup for article separation, comprising a rigid body, a vibrating member carried thereby and having an article engaging element, means for applying suction to said element, and means for causing vibrating movement between said vibrating member and said body.
4. A vibrating suction cup for article separation, comprising a rigid hollow body, a vibrating piston member carried thereby and partially enclosed by said body and having an article engaging element, means for applying suction to said element, and means for causing vibrating movement between said vibrating member and said body.
5. A vibrating suction cup for article separation, comprising a rigid body, a vibrating member carried thereby and having sliding movement therewith and having an article engaging element, means for applying suction to said element, and means for admitting air to a surface of said vibrating member to cause vibrating movement between it and said body.
6. A vibrating suction cup for article separation, comprising a rigid body, a vibrating member carried thereby and having an article engaging element surrounding one end of an air passage formed in said member, said element providing a suction chamber in communication with said air passage when the said element is in engagement with an article to be separated, and means utilizing other air passages associated with said vibrating member passage for raising and lowering said vibrating member relative to said body.
7. A vibrating suction cup for article separation, comprising a rigid hollow cylindrical body, a vibrating member carried by said body and having a cylindrical piston head movable therein and also having an article engaging element exterior of said body, suction means for conducting air through said member from its engaging element, and means associated with said suction means for alternately removing air from and admitting air to said piston head to vibrate said vibrating member.
